TRAILER

Lovel R. Simmons and Willie O. Ray, both of Jackson, Miss., assignors to M-R-S Manufacturing Company, Flora, Miss., a corporation of Delaware

Original application May 7, 1964, Ser. No. 79,878, now Design Patent No. 204,750, dated May 17, 1966. Divided and this application Oct. 5, 1965, Ser. No. 87,329

Term of patent 14 years

(Cl. D14—3)

The figure is a perspective view of a trailer showing our new design, the undisclosed side being the same as that shown and the rear being flat and plain.

This application is a division of our copending application Serial No. D-79,878, filed May 7, 1964 and now Patent No. D-204,750 for "Design for a Tractor Trailer."

The dominant features of the design reside in the solid line portion.

We claim:

The ornamental design for a trailer, substantially as shown and described.
